UNITED STATES PATENT OFFICE.

WATSON CUTHEBERT, OF ST. CATHARINES, ONTARIO, CANADA.

BROOM.

1,410,284.

Specification of Letters Patent. Patented Mar. 21, 1922.

Application filed March 5, 1920, Serial No. 363,624. Renewed December 31, 1921. Serial No. 526,418.

To all whom it may concern:

Be it known that I, WATSON CUTHEBERT, of St. Catharines, in the county of Welland, Province of Ontario, Dominion of Canada, have invented certain new and useful Improvements in Brooms, of which the following is the specification.

My invention relates to improvements in brooms and the like and the object of the invention is to devise a broom in which the straw portion and the handle are replaceable, independently, and which will be cheap and simple to manufacture.

My invention consists of a holder portion having a threaded orifice in the upper end, a wedge member within the holder, a straw portion adapted to be inserted into the lower part of the holder below the wedge, a handle threaded at its lower end and engaging the threaded orifice in the holder, the lower end of the handle co-acting with the wedge to force it into the upper part of the straw portion for securing it firmly in place in the holder all as more particularly described and illustrated in the accompanying drawings in which:

Figure 1 is a side sectional elevation of a broom constructed according to my invention.

Figure 2 is a sectional elevation on the line 2—2, of Figure 1.

Like characters of reference indicate corresponding parts in the different views.

1 is the holder portion having the threaded orifice 2. 3 is an unthreaded portion at the upper end of the orifice for a purpose to be described hereinafter. 4 are upright ribs extending inwardly from the inner wall of the holder. 5 is a beaded portion at the lower edge of the holder. 6 is a ridge extending inwardly from the holder wall. 7 is a wedge having the groove 8 extending around it near its upper end and having a hole 9 located centrally on its upper face. 10 is the handle having the lower part threaded as at 11 and provided with the centering pin 12 depending centrally from its lower end. 13 is the straw portion having the single row of stitching 14.

My broom is constructed as follows:

The wedge 7 is placed in the holder. The upper end of the straw portion 13 is now inserted into the holder until it engages the ridge 6 which forms a stop therefor. The handle is screwed into the holder and in so

doing it engages the wedge and forces same down into the straw. As the wedge is forced down into the straw it presses the straw between the holder walls and the wedge so that the straw is held firmly in place. The beaded portion 5 and the groove 8 assist greatly in holding the straw which is bent about these parts as will be seen from Figures 1 and 2. The wedge is so shaped that a great pressure is exerted upon the straw between the wedge and the bead 5 (note Figure 1). After the straw has been inserted into the holder and the wedge 7 forced thereinto, since the single row of stitching 14 is located near the upper end, the straw flares out at the lower end thereof giving a good sweeping surface. While the handle is being screwed down the pin 12 engages the hole 9 in the wedge and the ribs 4 form guides therefor so that the wedge is maintained in a strictly central position as it passes into the straw thus ensuring that an equal pressure will be exerted on the straw at all points. By having the thread in the orifice 2 ending below the top of the holder there is less likelihood of breaking the handle as the same is of full cross section at the point where the greatest strain is exerted.

In assembling the broom the stop 6 ensures that the straw will be inserted exactly the proper distance into the holder.

In the ordinary type of broom much longer and more expensive straw must be used than is the case with a broom made according to my invention for which short and cheap straw is quite suitable. A further advantage of my broom lies in the cheapness of manufacture as there is no expert workmanship required. In manufacturing the ordinary broom, an expert broom-maker must be employed which is not necessary in making my brooms. Again I further reduce the cost of manufacture by having only one row of stitching whereas the ordinary broom has several. This single row of stitching is required only to give the sweeping edge of the broom the proper flare.

The greatest advantage of my broom is of course the feature whereby the straw portion can be renewed independently of the other parts so that the broom will last a life time and when the straw is worn out only a very small outlay is involved in making the broom as good as new.

While the use of my broom for household work will result in a considerable saving

its greatest field will probably be for factory use where the straw portions can be purchased cheaply in large quantities and after the original cost of the required number of holders the maintenance cost will be very small. It will, of course, be noticed that in case the handle gets broken it is replaceable independently of any other part.

From the foregoing it will be seen that I have devised a broom which will enable a very great saving to be effected by practically the whole community.

What I claim as my invention is:

A broom comprising a straw portion, a hollow holder therefor, its lower end adapted to receive the upper end of the straw portion, a horizontal partition within the holder adapted to engage the upper end of the straw portion, a downwardly directed wedge slidably carried within the holder and

engaging an orifice in the partition, vertical guides within the holder engaging the sides of the wedge, the holder portion having a centrally located, threaded orifice in its upper end, a handle portion having its lower end threaded, said threaded part of the handle engaging the threaded orifice in the holder, a depending pin carried by the lower end of the handle and engaging a centrally located orifice in the top side of the wedge, an inwardly disposed bead extending around the lower end of the holder, the wedge having a surrounding groove therein near its upper end, the wedge adapted to be forced downwardly into the straw portion when the handle is screwed into the holder.

WATSON CUTHBERT.
